UNITED STATES PATENT OFFICE.

CHARLES LEAVER, OF IMPEROYAL, NOVA SCOTIA, CANADA, ASSIGNOR TO IMPERIAL OIL, LIMITED, A CORPORATION OF CANADA.

ART OF REFINING OILS.

Application filed March 11, 1921, Serial No. 451,532, and in Canada August 13, 1920.

The present invention relates to the refining of hydrocarbon oils and particularly to their refining by treatment with sulfuric acid, and will be clearly understood from the following description thereof, illustrated by the accompanying drawings, in which—

Figure 1 is a diagrammatic view illustrating an arrangement of apparatus suitable for carrying out the present invention. 10 Figure 2 is a longitudinal view through a portion of a mixing tube, showing the internal details of its construction.

Figure 3 is a vertical sectional view through the upper part of a treating tank, 15 and

Figure 4 is a sectional view on the line 4—4 of Figure 3.

In accordance with the present invention the oil to be refined is initially treated with 20 sulfuric acid, for example of 66° Baumé gravity, and may be subsequently treated with alkaline solutions, such as a solution of caustic soda, to effect its neutralization, and may be finally desulfurized or "sweetened" by means of the usual "doctor" or 25 sodium plumbate solution. The respective treatments of the oil are effected while the latter is in continuous movement through the apparatus and means are provided 30 whereby a thorough intermixture of the oil with the treating liquid is effected in the course of its movement.

Referring more particularly to Fig. 1, oil is introduced into the system through the 35 pipe 5 entering the mixing tube 6 through which it travels in the direction indicated by the arrow. During its movement it is thoroughly intermixed with the initial acid-treating liquid, which is preferably an acid 40 solution derived from the treatment with 66° acid of oil which has already been preliminarily subjected to the action of a weaker acid or acid solution. In the system illustrated the acid and the oil travel in 45 opposite directions, the acid first acting upon oil which has been initially treated with acid solution, and the acid solution used for this preliminary treatment is derived from the strong acid by its action on this 50 preliminarily-treated oil. The acid solution enters the mixing tube through the pipe 7 and travels therethrough in the same direction as the oil.

The construction of the mixing tube will 55 be clearly understood by reference to Fig. 2,

which shows a sectional view of a portion thereof. The mixing tube is formed by an outer tube 8, within which are arranged a plurality of longitudinally aligned pipe sections 9. These pipe sections are capped at 60 their ends by means of the imperforate caps 10, the caps of the adjacent pipe sections abutting against each other. The pipe sections 9 are supported in position in tube 8 by means of the rings 11 arranged midway of 65 the pipe sections, these rings being machined so as to hold the pipe section 9 securely and to fit tightly in the tube 8. The pipe sections are provided with numerous perforations on each side of the supporting rings 70 11. The oil and acid solution passing through the mixing tube are forced by the construction of the latter to follow the course indicated by the arrows in Fig. 2; that is, they are forced by the first of the 75 rings 11 to enter the first pipe section 9 through the perforations therein, and by the cap 10 at the end of the latter to pass out into the annular space surrounding the pipe section. A similar arrangement and construction of the succeeding pipe sections causes the mixture of oil and acid solution to travel in a similar manner through them, with the result that the liquids travel a zig-zag path through the mixing tube, flowing 80 into and out of the perforated pipe sections therein, and are very thoroughly intermixed.

The mixture of oil and acid solution passes out of the mixing tube 6 into the settling 90 tank 12, in which a separation of the acid sludge from the oil takes place. The sludge, which settles to the bottom, is drawn off through the valved pipe 13, and the oil passes out of the settling tank through the 95 pipe 14 which conveys it to the lower portion of the treating tank 15. The treating tank is provided interiorly with superposed baffles, the construction of which is indicated clearly in Figs. 3 and 4, Fig. 3 showing a portion of the treating tank in longitudinal section and Fig. 4 showing a transverse section thereof on the line 4—4.

The baffles are formed by the upwardly-tapering perforated cones 16 of sheet metal 105 or of suitable refractory material, and from which depend the conical frustra 17, which are open at their bottoms. At their lower edge the cones 16 are provided with up-standing rims or flanges 18. The lower 110

edges of baffles 16 and the upper edges of baffles 17 are secured to the rings 19, which are secured to the wall of the tank. Acid enters the treating tank through the pipe 20 above the uppermost baffle 16. The acid travels downwardly through the tank, inasmuch as its density is considerably higher than that of the oil, and the oil travels upwardly through the tank in counter-current to the acid. The arrangement of the baffles 16 and 17, and of the perforations thereof results in an intimate contact between the particles of the oil and acid in their travel through the tank. The acid sludge collects in the bottom of the treating tank and is withdrawn through the pipe 21, and forced into the pipe 7 through which it enters the mixing tube 6. The pump 22 may be provided in the line 21 to aid the movement of the sludge.

The acid-treated oil leaves the treating tank through the pipe 23, which conveys it to the settling tank 24, from which the oil passes through the pipe 25 into a wash tank 26. Bottom settling from the settling tank 24 are drawn off through pipe 27. Wash water is supplied into wash tank 26 through pipe 28 and settling are removed therefrom through pipe 29. From the wash tank 26 the oil passes through pipe 30 into settling tank 31, from which settling are drawn off through pipe 32. The treated oil passes through pipe 33 into the top of mixing tube 34, into which the alkali or soda solution enters through pipe 35. The oil and alkali solution travel through the mixing tube together, being thoroughly intermixed, and enter the settling tank 36, in which the alkali solution separates to the bottom and is withdrawn through the valved pipe 37. The oil rises to the top of the settling tank 36 and passes out through the pipe 38 into the settling tank 39 which it enters at a point somewhat above the bottom of the tank. Settling are removed from tank 39 through

pipe 40, and the treated oil passes off through pipe 41, which may lead to a storage tank, if desired.

When sulfur is present in the oil or naphtha as sulfuretted hydrogen compounds, it is advantageous to dissolve litharge in the soda solution before treating the oil therewith. The weak soda-litharge solution, after removal from settling tank 36 through pipe 37, is forced by pump 42 through pipe 43 into settling tank 44, where lead sulfid is settled out. The weak solution may then be run into storage tank 45. From tank 45 the weak solution may be withdrawn into mixing tank 46, where it is made up to its original strength by the addition of soda and litharge. This solution is then returned by pump 47 through pipe 35 to mixing tube 34.

Although the present invention has been described in connection with the details of a particular process for carrying it into effect and the apparatus for use in connection therewith, it is not intended that these details shall be regarded as limitations upon the scope of the invention, except in so far as included in the accompanying claims.

I claim:

1. The process of treating oils which comprises flowing the oil and a partially spent treating liquid concurrently through baffling obstructions, separating out the sludge, then flowing the treated oil in countercurrent to a stream of fresh treating liquid, the resulting partially spent treating liquid being used in the preliminary treatment of fresh oil.

2. The process of treating oils which comprises flowing the oil and acid sludge concurrently through baffling obstructions, separating out the sludge, then flowing the oil counter current to a stream of fresh sulfuric acid, separating the sludge from this step of treatment and flowing it with fresh oil through the first step of treatment.

CHARLES LEAVER.
